Specification of Letters Patent.

Patented Apr. 3, 1917.

Application filed May 27, 1913. Serial No. 770,140.

To all whom it may concern:

Be it known that we, JOHN P. EUSTIS and ALBERT T. BROWN, citizens of the United States of America, residing, respectively, at 5 Newton, county of Middlesex, State of Massachusetts, and Arlington, county of Middlesex, State of Massachusetts, have invented new and useful Improvements in Pneumatically - Operated Musical Apparatus, of which the following is a specification.

This invention relates more particularly to pneumatically operated musical apparatus of the class in which the pneumatic mechanism is located within the piano case, 15 although the invention is equally applicable to that class in which a separate case containing the actuating mechanism is moved up to the key - board of the piano. In prior constructions the wind chest and 20 comitant parts such as the end cheeks or boxes are of wood and the tracker tubes are of rubber, but under the present invention these parts are preferably constructed of metal such as high sheet brass. Where the 25 wind chest and cheeks are constructed of wood, the walls thereof are necessarily thick, and the necessary holes cut into the wood are more or less rough. One of the objects of the present invention is to construct the said 30 parts of sheet metal, with the result that the aggregate length of the wind passages is considerably reduced, as the holes are in thin metal and not in thick wood, and the metallic walls of the holes may be made smooth.

Other general objects of the invention are to provide in the parts metallic leak-proof joints, to reduce the parts to as small compass as is consistent with efficient service, to 35 practically preclude interference with sound waves by the saving of friction in the numerous passages, which would otherwise pass through thick wooden walls to increase the resonance, to provide a construction which is not affected by atmospheric conditions, and to preclude the opening of the 40 joints between the wind chest and end cheeks or other parts due to the sagging of the wind chest, etc. Another or special object of the invention is to construct the wind 45 chest and the end cheeks of metal in practically square form, whereby a substantially unimpeded column of air may pass through the wind chest owing to the fact that little or no frictional resistance thereto is offered by 50 the square corners, inasmuch as they are re-

moved although not remote from such column of air. Such square corners of course offer more resistance than the surfaces of the walls between them, and consequently the entire column of air in the wind-chest will 55 move at substantially the same speed at points between said corners, while those portions of said entire column of air which are directly in said corners are retarded. Other objects of the invention will appear throughout the specification. 60

These being among the general objects of the invention, the same consists of certain features of construction and combinations of parts to be hereinafter described and then 65 pointed out in the claims with reference to the accompanying drawings illustrating one desirable form of the invention, and in which—

Figure 1 is a front elevation of parts of 70 the piano case with the present improvements applied thereto;

Fig. 2 is an enlarged vertical section of 75 one of the cheeks of the wind chest, taken on the line 2—2 Fig. 1;

Fig. 3 is a vertical section on the line 80 3—3 Fig. 2, showing other improved parts associated with said cheek;

Fig. 4 is a transverse section on the line 85 4—4 Fig. 2, showing clearly how one end of the wind chest is removably attached to the piano case;

Fig. 5 is a vertical section on the line 90 5—5 Fig. 3;

Fig. 6 is a transverse section through the 95 wind-chest, showing parts supported thereby such as the controlling valves, actuating pneumatics and tracker tubes;

Fig. 7 is a transverse section, with parts 100 omitted, on the line 7—7 Fig. 1;

Fig. 8 is a vertical section through the other cheek of the wind-chest, taken in the plane of the wind-chest;

Fig. 9 is a vertical section on the line 105 9—9 Fig. 8, showing more particularly how the said cheek is secured to the piano case;

Fig. 10 is a sectional detail partly in elevation, showing how the strikers are guided;

Fig. 11 is a plan of the same parts;

Fig. 12 is a detail transverse section, 110 showing how the sections of the tracker tubes are joined together and supported;

Fig. 13 is a plan of the same parts; and

Fig. 14 is a section on the line 14—14 Fig. 1, showing how the metallic tubes are 115

supported back of the music roll casing and how the same are connected with the tracker bar.

Referring to Figs. 1, 2 and 9, the piano case 10 is provided with a pipe 11 which supplies air to the foot exhaust bellows, and on the said case are supported a left-hand bracket 12 and a right-hand bracket 13. The bracket 13 is provided with an opening or chamber 14 to which the tension pipe 11 leads, and also with an opening or chamber 15 to which leads a pipe 16 connected with another pipe corresponding with pipe 11 and with one of the expression pneumatics not shown, but well understood in mechanism of this description. A pipe 17 leading to an opening or chamber 12^a in bracket 12 is connected with another expression pneumatic. The said expression pneumatics in the illustrated form of the apparatus are intended to position the hammer rest rail.

The tracker bar 18 is mounted in the music roll case and frame 19, and a motor 20 and roll operating mechanism 21 are provided which may be controlled from governor 22.

There is an upper wind-chest 23 and a lower wind-chest 24 which extend parallel with each other and are connected with a left-hand cheek or box 25 and a right-hand cheek or box 26. There are also pneumatic valve units 27 mounted upon the upper wind-chest and pneumatic valve units 28 mounted upon the lower wind-chest, and these valve actions are adapted to actuate the striker pneumatics 29 and 30.

All the above described parts may be of any well-known or desirable construction, with the exception that the wind chest and end cheeks are preferably constructed in accordance with the present invention. Each wind-chest 23, 24 is preferably made of drawn seamless metal tubing, and the cross section thereof is square or substantially so. The same also applies to the end cheeks or boxes 25, 26. Seamless metal tubing is desirable although not absolutely necessary, but seamless tubing absolutely prevents any leakage throughout its length.

Referring more particularly to Figs. 2, 3, 4 and 5, the cheek or end box 26 is provided at the wall facing the wind-chests 23, 24 with openings which are surrounded by outwardly extending flanges or collars 31 struck up from the metal of the cheek 26. The interior dimensions of the collars 31 are just sufficient to take with a snug fit the end of the wind-chests 23 or 24 to be applied thereto, the wind-chest end being inserted within the collar, whereupon bushings 32 are applied from within the end cheek 26 to the ends of the wind-chests 23, 24, and each of said bushings has an external flange 33 which seats upon the inner wall of the said cheek. The so described parts have in the first instance a snug fit, and solder is pref-

erably applied to the said joints so that they are absolutely leak-proof. It will be seen that there are three thicknesses of metal at each of these joints so that the wind chest and the said end cheek 26 are rigidly and substantially secured to each other. The said end cheek 26 rests upon the lower support of bracket 13, and the wall thereof which is applied next to the opening or chamber 14 is provided with an opening which is surrounded by an annular flange 34 which is struck up from the said wall and turned inwardly into the cheek, whereby the edge of the opening in the said cheek is reinforced. Likewise a similar flange 35 is struck up from the upper end of the said box where the opening surrounded by said flange communicates with chamber 15 in bracket 13. Applied against the upper walls of the end cheek or box 26 are flanged sleeves 36 and through these pass with a snug fit an upper tube 37 which leads to the governor 22, while similar flanged sleeves 38 are applied to the walls below the sleeves 36, and through these passes a lower tube 39 which also leads to the governor. The said tubes 37 and 39 serve to control the governor in a manner known in the art and may be soldered in position where they pass through the walls of said cheek, and likewise the said sleeves may be soldered in position, so as to provide a leak-proof joint. The upper end of the end cheek 26 is closed in part by a top plate 40 having an external depending flange 41, the form of which corresponds to the inner cross-section of the said cheek plate so that the said flange may have a snug fit therein. There is also at this point a cap-plate 42 which is provided with an opening surrounded by a struck up annular flange 43, and the said cap-plate 42 is secured in position preferably by means of lugs 44 struck up from the inner plate 40. Between the plates 40 and 42 a sheet of packing material 45 is placed. At the top of the end cheek 26 is a dome or spherical chamber 46 with which is connected pipe 47 which leads to the governor. Mounted within the upper end of the cheek or end box 26 above the wind-chest 23 is an anchor plate 48 which is provided with an up-turned flange 49 which fits against and is suitably secured to the inside of the end cheek 26. Said plate 48 is provided with a central opening which receives a flanged bushing 50 which is soldered therein and screw-threaded to receive the screw-threaded end of a stay-bolt 51, the head of which is drawn against the dome 46, whereby the parts are removably secured together so that access may be had to the inside of the upper end of the cheek 26. If desired, the said plates may be soldered in position. The soldering of bushing 50 provides an air-tight joint at this point, and prevents leakage to either side

of the anchor-plate 48, which really constitutes a partition separating the cheek 26 into two compartments.

Means are provided for attaching the 5 wind-chests 23 and 24 through the medium of end cheek 26 and concomitant parts to the corresponding end of the piano case. To this end, as more clearly shown in Fig. 4, the end cheek 26 is provided with a transverse 10 tubular brace 53 which is of the same length as the distance between opposite walls of said cheek so that the ends of said brace will form butt joints with the said walls. The walls of the end cheek 26 opposite the 15 open ends of the tubular brace 53 are provided with openings, which receive bushings 54 and 55 which are inserted through said openings and into the ends of the tubular brace 53, the fit being a snug one. The outer 20 flanges of these bushings project over the outer walls of the said end cheeks, and through the said bushings passes a set screw 56 provided with a knurled head 57, the shank of said screw passing through the said 25 tubular brace 53, and being provided with a screw-thread 58 so that the said set screw may have a screw connection with bracket 13. Under the knurled head 57 of the set screw is confined a packing ring 59. It will 30 be seen that when these parts are screwed up tight, a perfectly air-tight joint connection is provided and that the said parts are firmly supported against and upon the bracket 13. The set screw 56 provides means for remov- 35 ably securing the described end of the wind-chest parts to the piano case. Preferably, a packing strip 60 is placed between the cheek 26 and the vertical wall of the bracket 13. The said end cheek 26 is furthermore pro- 40 vided with a bottom plate 61, flush with the lower edge of the said cheek and provided with an external struck up flange 62, which is tightly fitted into and soldered to the lower end of said cheek. A middle separa- 45 tor column 63 may connect the wind chest 23 with the wind chest 24 between the end cheeks 25, 26, and this column may be externally flanged and the flanges soldered to the walls of the wind-chest. It therefore 50 acts as a support for the upper wind-chest.

At the left-hand ends of the wind-chests 23 and 24 is a cheek or end box 25 before mentioned, and its construction is more particularly shown in Figs. 8 and 9. Said 55 cheek is provided with a top plate or cap 64 having an external flange 65 fitting into the upper end of the said cheek, and there is also a bottom plate or cap 66 likewise provided with an external flange 67 fitting into the 60 lower end of the said cheek. The said plates 64 and 66 are of sheet metal and to the joints between the parts solder is applied, as is also the case of the corresponding plates for the right-hand cheek. A joint connecting 65 each wind-chest 23 and 24 with the left-hand

cheek 25 is provided which is the same as the joints connecting the right-hand cheek with the said wind-chest, the external flange or collar on the cheek 25 being indicated by 68 and the internal flanged bushing by 69, and thereby a three-ply construction similar to the construction of the corresponding joints at the right-hand end of the wind-chests is provided. The cylindrical portion 70 of bracket 12 and which contains chamber 12^a is provided at its outer end with a screw neck 71, while the remote wall of the cheek 25 is provided with an opening 72 over which is applied a reinforcing cover-plate 73 which also has an opening into which and through said opening 72 a flanged bushing 74 is inserted. A set screw 75 is also provided, and this has a knurled head 76 so that when the shank of said screw is passed through the said bushing, the threaded end of the screw may be screwed into the neck 71 and the parts thereby tightly set. Under the head 76 of said screw is a packing ring 77, so that in connection with this packing ring, and the bushing 74 and the plate 73 which are soldered together and to the said cheek, a leak tight joint is provided. Between the cheek 25 and the vertical wall of bracket 12 a packing strip 78 is preferably placed to form an air-tight joint, and this packing has 95 an opening which registers with an opening 80 in the adjacent wall of said cheek, which opening 80 is surrounded by an in-turned annular flange 79, which reinforces the said wall of said cheek. By means of the set screw 75, the left-hand end of the described wind-chest structure is removably secured to the corresponding side of the piano case.

Referring to Figs. 1 and 6, the preferred tracker tube construction will now be described. In the illustrated embodiment of the invention two wind-chests are shown, in which case there are two sets of tracker tubes, namely 81 and 82. These tracker tubes connect in a well-known manner with the diaphragm chambers 83 of the valve action, 84 indicating the flexible diaphragms. The said tracker tubes are formed of metal tubing and their forward ends extend through openings in depending front flanges 105 85 and 86 respectively on the upper and lower wind-chests. The said flanges extend lengthwise of the wind-chests and are preferably formed as depending portions of plates or metal strips which are soldered or brazed 110 to the front walls of the wind chests, whereby the said wind-chests are reinforced and stiffened. It will be noted that by means of these depending flanges 85 and 86, the tracker tubes are located wholly outside of 115 the wind-chests and do not pass therethrough, so that there can be no leakage in this connection. The tubes 81 and 82 have been designated tracker tubes but in reality in the preferred embodiment of the present in- 120 125 130

vention they constitute lower sections of the tracker tubes which will be fully described hereinafter. For supporting and fixing the upper ends of the tracker tube sections 81 and 82, juncture brackets 87 are provided, which are secured by screws or in any other suitable manner to an angle bracket 89 which is soldered or otherwise fixed to the back of the wind-chest. There are of course two of these brackets 89, because the pneumatics 29 and 30 are preferably supported on said brackets 89. Through the said brackets 89 and between the brackets 87 the metallic tracker tube sections 82 pass, while tracker tube sections 81 pass through the lower bracket 89. Said brackets are also preferably constructed and bent up from sheet metal. It is obvious that when the upper ends of the tracker tube sections 81 and 82 are all secured to a plate 90, the parts are mutually stiffened and braced. Carried by the brackets 87 is a capstan guide plate 90 also preferably of sheet metal, and as shown more particularly in detail in Fig. 12, holes 91 are provided in capstan guide plate 90, into which the upper ends of the tracker tube sections 81 and 82 are inserted and in which plate 90 they may be soldered. Opposing the plate 90 is a supplemental juncture plate 92 provided with holes 93, which are arranged to register with the holes for the tracker tube sections 81 and 82, and into these holes 93 the ends of the other sections 94 of the metallic tracker tubes are inserted and soldered if desired. Located around the upper ends of the tracker tube sections 81 and 82 are flanged collars 95, and have a snug fit thereon, and which are soldered or otherwise secured to the underside of the guide plate 90. Likewise flanged collars 96 are snugly fitted about the lower ends of the upper tracker tube sections 94, and these may be soldered or otherwise secured to the supplemental plate 92. Confined between the capstan guide-plate 90 and the supplemental plate 92 is a strip of packing material 97 which is provided with holes which register with the adjacent ends of the tracker tube sections 81, 82 and 94. Screws 97^a pass through the plates and packing and firmly unite the parts. By this construction a suitable leak-tight connection is provided between the lower sections of the tracker tubes and the upper sections, and a rigid construction is provided.

Referring to Fig. 14, it will be seen that the upper ends of the upper tracker tube sections 94 are anchored or fixed back of the music roll box or casing 19, and said upper ends extend through the outwardly projecting flange of an angle plate or bracket 98 which is soldered or otherwise secured to the casing 19 and extends transverse thereof in a position substantially parallel with the tracker 18. To the said plate 98 the upper

ends of all of the tracker tubes, usually eighty-eight in number, converge. Preferably where the upper sections of the tracker tubes so closely lie together, solder is placed between them so that a rigid construction is provided. Around the upper ends of the tracker tube sections 94, flanged collars 99 are placed and may be soldered thereon and to the angle plate 98. The upper ends of the metallic tracker tube sections 94 protrude slightly above the angle plate 98 so as to furnish necks with which short rubber tube sections 100 are connected, which are in turn connected in a well-known manner to the tracker bar 18, so that atmospheric air admitted through the perforations in the perforated music sheet will enter the tracker tubes and play the instrument.

Striker guide plate 90, Figs. 6 and 10, is provided with a number of openings extending parallel with the wind-chest, and in these openings are set metallic shells 101 or guides, and each of these shells is contracted at 102 where it is fixed to the guide-plate 90, due to the fact that each shell flares from said intermediate point 102 toward both ends of the shell. These shells are preferably seamless, and are provided with soft felt or leather linings 103. Guided in the guide shells 101 are the strikers 104 which are connected in any suitable or well-known manner with the movable leaves or members of the actuating pneumatics 29 and 30. When the parts of the described apparatus are in position, the upper ends of the strikers will be in contact with the undersides of the wippets 105 of the various hammer actions of the piano.

The described actuating mechanism is as before explained, provided at each end with a set screw or other equivalent fastening device so that the said mechanism is secured at two points only to the piano case, and may be removed therefrom.

As shown in Figs. 1 and 7, the lower wind-chest 24 has applied thereto forks 111 downwardly from which extend forks 112. The forks 112 are bent outwardly so as to constitute feet so that when the described mechanism is removed from the piano case, the same may be supported upon any supporting surface by means of said feet, with sufficient elevation to carry the mechanism out of contact with the supporting surface so that the said mechanism may be inspected, regulated and adjusted as desired. Preferably the fork 111 and the fork 112 are formed from one metal casting.

A valuable feature of the present invention resides in maintaining a sufficient state of tension in the wind-chest and other passages of the mechanism. This is in part due to the metallic construction and in part to the nature of the joints between the various conducting elements of the mechanism,

- which joints are soldered, brazed or welded wherever desirable. This augments the permanency of atmospheric tension under varying climatic conditions and consequently 5 standardizes the power upon which all tone color or musical expression depends. It is obvious that when the pumping pedal of a player-piano or equivalent musical instrument is depressed, the effect upon a note of 10 the piano should be equivalent to the actual pounds pressure upon said pedal as though the latter were connected directly to the key by some mechanical means. In prior pneumatic instruments this is not true owing to 15 leakage and the percolation of vacuum tension through packing and joints which necessarily must be made to be separable. To diminish the number of such joints in a player-piano augments the directness of the 20 power exerted upon the pedal. Any loss in the vacuum tension thus produced through faulty joints in the air passages of the player-piano results in loss of power, loss of tone color and consequent loss of musical 25 expression. Therefore, the result attained by the pneumatic instrument is made superior just in proportion as its vacuum tension can be conserved and just in proportion to the smallness of all the parts handling this 30 vacuum tension, it being understood that the less atmosphere one has to stretch or bring up to the vacuum tension, the easier is the work of the operator and the less tiresome and irksome becomes the execution of the 35 work. It will be seen from the above description of the present invention that while the mechanism is apparently compact and is relatively small as compared to the old wooden structure, that the capacity of the 40 air chambers or passages is relatively large, and this difference is considered to be material in the operation of the instrument.
- It is obvious that the present invention is susceptible of a wide range of modification, 45 as parts may be omitted, parts added and parts substituted without departing from the general spirit and scope of the invention.
- What we claim as new is:
1. In a pneumatically operated musical apparatus, a wind-chest structure of sheet metal, the same comprising a wind-chest and hollow end cheeks joined thereto, the opposing inner walls of said end cheeks having 50 outdrawn flanges into which the ends of said wind-chest fit.
  2. In a pneumatically operated musical apparatus, a wind-chest structure of sheet metal, the same comprising a wind-chest and hollow end cheeks joined thereto, the opposing inner walls of said end cheeks having 55 flanges into which the ends of said wind-chest fit, and flanged bushings inserted into the ends of said wind-chest.
  3. In a pneumatically operated musical 60 apparatus, the combination with a wind-
  - chest and hollow end cheeks, of a leak-tight and soldered joint between them, located at each end of said chest comprising three thicknesses, all of said parts of metal. 65
  4. In a pneumatically operated musical 70 apparatus, a hollow metallic wind-chest cheek, and metallic flanged cap plates inserted in each end thereof and permanently joined air-tight thereto.
  5. In a pneumatically operated musical 75 apparatus, the combination with a hollow metallic wind-chest cheek, of a transverse tube the ends of which abut against the opposite inner walls of said cheek, and metallic bushings inserted in the ends of said tube 80 and secured to the outer walls of said cheek.
  6. In a pneumatically operated musical 85 apparatus, the combination with a wind-chest and a hollow wind-chest cheek, of an inner anchorage plate constituting a partition in said cheek above said chest, a removable dome applied to said cheek above said partition, and a bolt from said dome removably applied to said anchorage plate. 90
  7. In a pneumatically operated musical 95 apparatus, the combination with a wind-chest and a hollow wind-chest cheek, of an inner anchorage plate constituting a partition in said cheek above said chest, a removable dome applied to said cheek above said partition, and a bolt from said dome removably applied to said anchorage plate, all of said parts being of metal and, except for the said removable parts, being rigidly united as by soldering or brazing. 100
  8. In a pneumatically operated musical 105 apparatus, the combination with a wind-chest and a hollow wind-chest cheek, of an inner anchorage plate constituting a partition in said cheek above said chest, a removable dome applied to said cheek above said partition, a bolt from said dome removably applied to said anchorage plate, an air pipe connected with said cheek at a point above said partition or plate, and a 110 second pipe connected with said dome.
  9. In a pneumatically operated musical 115 apparatus, the combination with a wind-chest and a hollow metallic wind-chest cheek, of an inner anchorage plate constituting a partition in said cheek above said chest and separating said cheek into two separate passageways, a cap plate applied to one end of said cheek, a dome thereon and a screw bolt connecting said anchorage plate 120 and dome, whereby a detachable connection is provided.
  10. In a pneumatically operated musical 125 apparatus, the combination with a metallic wind-chest having a metallic flange permanently united to said chest along and in a plane parallel with one wall thereof as by brazing, of tracker tubes extending through said flange and thereby rigidly anchored to said chest. 130

11. In a pneumatically operated musical apparatus, the combination with a metallic wind-chest having a metallic reinforcing plate for one wall permanently united thereto along said wall as by brazing and providing a flange projecting from said chest, of tracker tubes supported by said flange. 5
12. In a pneumatically operated musical apparatus, the combination with a wind-chest and a bent-up sheet metal bracket secured thereto and having a substantially horizontal flange, of a pneumatic supported from said flange so as to extend across said chest. 10
13. In a pneumatically operated musical apparatus, the combination of a wind-chest, a metallic bracket plate rigidly secured to but not constituting one wall thereof and extended beyond the adjacent wall, metallic tracker tubes extending through and anchored to said extension of said bracket plate, and valves on said chest to which said tubes lead. 15
14. In a pneumatically operated musical apparatus, a metallic angle bracket, a metallic bracket plate, said bracket and plate being permanently secured to opposite sides of said wind-chest as by brazing and extending beyond one wall of said wind-chest, metallic tracker tubes extending through and anchored to said bracket and plate, and valves on said chest to which said tubes lead. 20
15. In a pneumatically operated musical apparatus, the combination with tube supporting means, of sectional metallic tracker tubes supported by and having a juncture at said supporting means, said supporting and juncture means comprising a supporting plate, having holes into which the ends of some of said sections are secured, a supplemental plate having holes into which the ends of other of said sections are secured, means for packing the joint between said plates, sleeves secured by solder around said sections and to said plates, and fastening screws passing through the said plates and packing means. 25
16. In a pneumatically operated musical apparatus, means for supporting one end 30

of a wind-chest, comprising a hollow cheek having aligned openings in opposite walls, a tubular brace of greater diameter than said openings and having abutment at both ends against the said walls, a support, and a fastening bolt extending through said cheek and brace and removably secured to said support. 55

17. In a pneumatically operated musical apparatus, means for supporting one end 60 of a wind-chest, comprising a hollow cheek, having an opening in one wall, a plate or disk secured against the opposite wall, a bushing inserted in said plate, a support, and a removable fastening bolt passing 65 through said bushing and opening and secured to said support.

18. In a pneumatically operated musical apparatus, the combination of the case for the parts, and said parts, comprising a wind-chest, hollow upright end-cheeks connected with the said chest, a passage leading to one of said cheeks, means for detachably connecting the lower ends of said cheeks with said case and one of them with said 75 passage, the said latter cheek having a transverse partition above said chest, a closure above said partition, a passage led in between said partition and closure, and a passage 80 from the governor to said closure. 80

19. In a pneumatically operated musical apparatus, the combination of the case for the parts, and said parts, comprising a wind-chest, hollow upright end-cheeks connected with the said chest, a passage leading to 85 one of said cheeks, means for detachably connecting the lower ends of said cheeks with said case and one of them with said passage, the said latter cheek having a transverse partition above said chest, a removable 90 hollow closure above said partition, a fastening connecting said closure with said partition, a passage led in between said partition and closure, and a passage from the governor to said closure. 90
